UNITED STATES PATENT OFFICE

ROBERT A. MUELLER, OF HOUSTON, TEXAS

COMBINATION TUBING HANGER AND BLOW-OUT PREVENTER

Application filed April 16, 1931. Serial No. 530,849.

The invention relates to an improvement in casing heads wherein certain mechanisms are combined in the casing head to enable a complete closing of the well bore inside and 5 outside of the tubing.

Various types of casing heads have been devised heretofore in which the tubing has been suspended in the well. However, it is often desirable when changing the fittings 10 above the well to entirely close off the well bore inside and outside of the tubing so that appropriate changes or alterations may be made in the other fittings. With the idea in mind of providing a quickly removable tubing hanger which will permit closing of the 15 flow of fluid through the tubing and with the idea of providing a closure around the outside of the tubing, the present assembly has been devised.

It is one of the objects of the invention to provide a tubing hanger and blowout preventer which may be assembled on the well as a unitary structure.

Another object of the invention is to provide the invention with a blowout preventer for the well casing and a combination tubing head and a blowout preventer for the tubing.

Another object of the invention is to provide a blowout preventer wherein the rams are adapted to engage each other at an inclination.

A still further object of the invention is to provide complete closure for the well casing and tubing by assembling two blowout preventers on the same well.

Still another object of the invention is to provide a combination blowout preventer and tubing hanger which may be readily attached 40 to the well tubing and seat in position when the tubing is landed on the casing head.

It is also an object of the invention to provide in combination a blowout preventer, a tubing hanger and a tubing closure means on 45 a well head assembly.

Still another object of the invention is to provide a pressure-operated blowout preventer wherein the pressure is applied by a hand pump which may be manipulated to 50 extend or retract the preventer rams.

While a certain form of the invention has been disclosed it is intended that various modifications and alterations may be made in the structure and operation thereof as the appended drawing merely illustrates one form 55 of the invention, and in this drawing

Fig. 1 is a side elevation of a casing head assembly arranged in accordance with the present invention and showing certain parts 60 in section.

Fig. 2 is a sectional view taken on the line 2-2 of Fig. 1 and looking in the direction of the arrows.

A well casing is illustrated at 2 and is of the usual type which is cemented or otherwise 65 anchored in the earth and extends to the surface in order to act as a support and anchor for the various fittings that are to be placed upon the well. It is usual to attach to this casing any fittings which are necessary in 70 order to control the flow of fluid from the well and in the present illustration a blowout preventer 4 is shown as attached to the casing 2 by the flanged connection 5. It is to be understood that this blowout preventer 75 may be of any type which is adapted to close about a drill stem or string of pipe which is in the well, and for purposes of illustration a well known type of blowout preventer has been illustrated.

This preventer is known as the Cameron blowout preventer and may be of the pressure-operated type wherein fluid pressure is applied through the lines 6 in order to move the rams inside of the housing 7 so that they 85 will close about the outside of a pipe such as 8, which may be in the well. It is usual to place a blowout preventer of this type on the casing during the drilling operation so that in event a high pressure formation is encountered the blowout preventer may be closed about the drill stem in order to seal off the area such as 9 inside of the casing. However, when tubing is run into the well after the drilling has been completed, it is also 90 desirable to close off the area 9 in event the well begins to blow out and particularly so while the tubing is being run into the well, because if the well has not been mudded in or killed by filling it with mud, considerable 95 100

pressure is usually encountered and some means must be provided to close off this pressure in event of emergency so that the blowout preventer such as 4 is retained on the casing when the tubing is positioned. It is to be understood that the rams of the blowout preventer 4 have semi-circular cavities in the faces thereof so that the two rams will co-operate to close about the pipe 8. Control of the blowout preventer to cause movement of the rams is accomplished by means of the control handle 10.

After the drilling has been completed it is usual to run a string of tubing, which may be represented by the pipe 8, into the well in order to flow the oil therefrom. This string of tubing extends to the bottom of the well and may have suitable perforated screen pipe or other filtering devices on the lower end thereof. This tubing is arranged to be supported by a hanger structure 11, which is in turn mounted on a casing head 12. The casing head may have been present during the drilling operations and the flow lines 13 and 14 used to discharge the flow of flushing fluid used in the drilling operation, and the tapered bowl 15 thereof used to support slips or pipe-engaging means when the drill pipe is being raised or lowered into the well. It is understood that suitable valves may have been placed upon the lines 13 and 14 in order to close them in case of emergency. The short section of pipe 16 is in a sense a continuation of the casing 2 which has been placed in the upper side of the blowout preventer 4 in order to attach the casing head. When a heavy pressure is encountered in running the tubing into the well it is necessary that quick action be possible to insert the tubing and anchor it in position. In order to accomplish this a combination tubing hanger and blowout preventer has been provided which is indicated generally at 11. This hanger includes a housing or body portion 18, which is formed with a threaded connection at 19 to receive the string of tubing 8. These threads 19 are formed on the skirt 20 of the hanger, which is shown as tapered on its outer surface at 21 in order to seat in the bowl 15. If desired, suitable packing rings 22 may be provided on the outside of the skirt to engage against the bowl 15. Above the skirt 20 the body 18 is formed with an outstanding flange 23, which is arranged to seat upon the flange 24 of the casing head and be retained in position by bolts or other fastening elements 25. A suitable packing 26 may be positioned between the two flanges so that a complete seal will be possible when the nuts 27 are drawn tightly on the bolts 25. In this manner the tapered skirt 20 will be wedged into the bowl 15 and a positive seal assured. In positioning this combination tubing

hanger and blowout preventer it is intended that it will be attached to a section of pipe such as 8, which is to be the topmost section of the string of tubing, and may then be suspended in the well so that this section of tubing may be quickly connected to the coupling which is usually up on the piece of pipe being lowered into the well. Thus, if an emergency arises it is only necessary to connect this section of pipe to the coupling and drop it into position in the bowl 15 and affix the bolts 25 so that the tubing is properly suspended and the tubing head will be anchored in position.

In order to close off the passage 30 through the tubing the housing 18 has been provided with a pair of rams 31. These rams are arranged for movement in the chambers 32 and may be actuated by means of fluid pressure in the lines 33. Particular attention is directed to the inclination of the chambers 32 and the rams 31 with respect to the passage 30. With this construction the contact faces 34 of the rams are inclined with respect to the body portion 35 thereof. In this manner the contact faces are of greater area than they would be if the rams moved in a horizontal plane and a greater wedging action of one ram against the other may be obtained in this manner.

The inclined faces 34 abut against each other when the rams move downwardly and the wedging action of these two faces forms a much more efficient seal between the two rams than can be formed with devices which move in a horizontal plane. In addition, the surface 37 is presented to the pressure occurring in the pipe 8 and this pressure will be added to that in the chamber 32 in order to assist in providing a seal between the two rams. If desired, packing 38 of any desired type may be positioned on the faces of the ram in order to insure a complete seal. It is also intended that suitable stop members or lugs to limit the inward movement of the rams 31 may be provided by co-operating members on the ram and the side of the chamber 32.

In order to operate the rams 31 pressure may be applied to the lines 33 through the pipe 40. This pipe 40 is coupled to a special valve 41, which contains a rotatable valve member 42, which is provided with two elbow passages 43. Leading from this valve 41 are three pressure lines 44, 45 and 46. 44 and 45 are connected to the discharge 47 and the inlet 48 of a pressure pump 49, while the line 46 leads to a supply reservoir 50. With the rotor 42 in the position shown in the drawing, operation of the pump will cause a flow of fluid in the direction indicated by the arrows on the pipe lines. It is intended that the discharge 47 and inlet 48 of the pump will be provided with suitable check valves so that a charge of fluid will be moved

on each stroke of the handle 51 of the pump. In this manner fluid will be passed through the lines 33 into the chambers 32 to move the rams downwardly to closed position.

5 When, however, it is desired to withdraw the rams it is only necessary to rotate the control member 32 so that the passage 43 instead of connecting the pipes 40 and 44 will then form a continuation to connect the pipes 40 and 45, whereas the passage 43' will then connect the pipes 44 and 46. If the pump is then operated the discharge thereof will be returned to the tank 50 and the suction of the pump will withdraw the fluid from the chambers 32 and in this manner the rams will therefore be moved to retracted position. With this construction it is only necessary for a single pump to accomplish operation of the rams and to insure proper manipulation thereof. In event, however, it is desired to operate the rams by hand, suitable thrust rods may be provided as is usual in such constructions and such a rod is illustrated at 52 on the blowout preventer 4.

25 The body 18 above the blowout preventer carries an upstanding connection 53, which is arranged to receive a pipe or flow line 54, which will lead to a suitable Christmas tree connection or may receive any other desired fitting.

With the present assembly it is possible to close the blowout preventer 4 about the tubing in order to close the area 9 and while this operation is being performed the tubing hanger 11 may be landed in position in the bowl 15 and the rams 31 closed so that in this manner complete closure of the area 9 and passage 30 will be provided by the manipulation of the two blowout preventers.

40 While the illustration of Fig. 1 contemplates the use of the second blowout preventer as part of the tubing hanger these two may be made as separate parts and a gate valve used as the tubing closure means if desired.

45 What I claim is:

1. A combination tubing hanger and blowout preventer including a body portion, means to seat said body in a casing head, a passage thru said body, means to connect 50 a tubing to said body in alignment with said passage, and means to close said passage, including a pair of downwardly inclined rams.

2. A combination tubing hanger and blowout preventer including a body portion, 55 means to seat said body in a casing head, a passage thru said body, means to connect a tubing to said body in alignment with said passage, said body including a pair of rams movable in said body at an inclination to the vertical axis thereof.

3. A combination tubing hanger and blowout preventer including a body portion, means to seat said body in a casing head, a passage through said body, means to connect 60 a tubing to said body in alignment with said

passage, said body including a pair of rams movable in said body at an inclination to the vertical axis thereof, and contacting faces on said rams disposed in the plane of the vertical axis of said body.

70

4. The combination with a casing head assembly of a tubing hanger, said casing head having outlets thereon, a blowout preventer on said hanger to close the tubing passage, and a blowout preventer on the casing below 75 said hanger to close about the outside of the tubing carried by said hanger below said casing outlets.

5. In a well head assembly a casing, a blowout preventer thereon to close said casing, a casing head having outlets above said preventer, a tubing hanger on said head, a tubing carried by said hanger, and a tubing closure means on said hanger.

80

6. In a well head assembly a casing and tubing, a blowout preventer thereon to close said casing about said tubing, a casing head having outlets above said preventer, a tubing hanger on said head, a tubing carried by said hanger, and a tubing closure means on said 90 hanger whereby said preventer may close off said casing, and said closure means may close off said tubing each independently of the other.

85

7. In a well head assembly a casing and tubing, a blowout preventer thereon to close said casing, a casing head having outlets above said preventer, a tubing hanger on said head, a tubing carried by said hanger, and a tubing closure means on said hanger.

95

8. In a well head assembly including a casing and tubing the combination of means to flow fluid from said casing and said tubing simultaneously or independently, and means to cut off the flow through said casing or said tubing below any openings in either of said casing or said tubing independently of each other.

105

9. The combination of a well casing having side outlets, a tubing therein, means to close off said casing around said tubing at an elevation below any outlets in said casing, and means independent of said first means to close off the passage through said tubing at an elevation below that of any openings therein.

110

10. In a well head assembly a casing and tubing, a blowout preventer on said casing to close between said casing and the tubing, a casing head having outlets thereon above said preventer, a tubing hanger on said head to support said tubing, and a second blowout preventer above said hanger to close off said tubing.

115

11. In a well head assembly a casing with side outlets, a blowout preventer thereon below any outlets on said casing, and a casing head above said preventer.

120

12. The combination of a well casing, a tubing therein, flow outlets on both said casing and said tubing, means in said casing to close

130

off said casing against the escape of fluid through said casing flow outlets, and means independent of said first means to close off the flow of fluid through said tubing at an elevation below said outlet therefrom.

In testimony whereof I hereunto affix my signature this 10th day of April, A. D. 1931.

ROBERT A. MUELLER.
